UNITED STATES PATENT OFFICE

2,593,364

WRITING TABLE HAVING AN ADJUSTABLE DRAWING BOARD

Percy W. Thompson, Memphis, Tenn.

Application August 9, 1949, Serial No. 109,256

1 Claim. (Cl. 311—38)

1

This invention relates to a table, and more particularly to a table for use by persons making signs and show cards.

The object of the invention is to provide a table which includes a drawing board that can be used in a horizontal position or readily moved to a sloping position as desired.

Another object of the invention is to provide a table that includes a drawing board which can be moved towards and away from the user in order to enable the user to work efficiently and comfortably.

Still another object of the invention is to provide a table which includes a novel means for adjusting the drawing board about a horizontal axis, or moving the board towards and away from the user, the structure including a means for maintaining the board immobile in its adjusted position.

Still another object of the invention is to provide a table which includes a drawing board that can be raised or lowered while the board is in a vertical or inclined position so that the user will be able to adjust his work to a convenient position, either up or down.

Other objects and advantages will be apparent during the course of the following description.

In the accompanying drawings, forming a part of this application, and in which like numerals are used to designate like parts throughout the same:

Figure 1 is a side elevational view of the table, with the drawing board in the raised position, according to the present invention;

Figure 2 is a rear elevational view of the table, with the board in the perpendicular position;

Figure 3 is a rear elevational view of the table, with the drawing board in its lowered or horizontal position;

Figure 4 is a vertical sectional view through the table, with the drawing board in the position of Figure 1;

Figure 5 is a sectional view taken on the line 5—5 of Figure 2.

Referring in detail to the drawings, the numeral 10 designates a supporting body which includes a pair of vertically disposed spaced parallel frame members 11 and 11'. A channel 12 extends between the lower portion of the frame members 11 and 11' while a similar channel 13 extends between the upper ends of the frame members 11 and 11'. The channels 12 and 13 are secured to the frame members by suitable securing elements, such as screws 14, Figure 1, and the channel members 12 and 13

2

serve to maintain the frame members 11 and 11' in their proper spaced relation.

Arranged above the frame member 11 is a channel shaped track 15, and arranged above the other frame member 11' is a similar channel shaped track 15'. Secured to one end of the track 15 as by welding is an ear 17, and a pin 16 hingedly connects the ear 17 to the frame member 11, there being a cotter pin 18 for maintaining the ear 17 on the pin 16. The other track 15' also has an ear 17' secured thereto, and a pin 16', Figure 4, hingedly connects the ear 17' to the frame member 11'. A pair of spaced parallel angles 18 and 18' extend between the tracks 15 and 15' and are secured thereto, as by welding, for a purpose to be later described.

From the foregoing description, it is apparent that the tracks 15 and 15' are adjustably mounted for pivotal movement about a horizontal axis. For maintaining the tracks 15 and 15' immobile in their adjusted positions, a stud pin 19 connects the upper end of a quadrant 20 to the track 15. The quadrant 20 slidably passes through a clamp bracket 21 which is secured to the frame member 11. A manually movable thumb screw 22 projects through the bracket 21 and into engagement with the quadrant 20 to maintain the tracks immobile in their adjusted position. Similarly, a stud pin 19' connects the upper end of a quadrant 20' to the track 15'. The quadrant 20' slidably projects through a clamp bracket 21' which is secured to the frame member 11', and a thumb screw 22' is carried by the clamp bracket 21' for engagement with the quadrant 20'.

Slidably arranged in the track 15 is a runner 23 which is preferably made of hard wood. An angle iron 24 is connected to the runner 23 by bolt and nut assemblies 25. Similarly, a hard wood run 23' is slidably arranged in the other track 15' and an angle iron 24' is secured to the runner 23' by suitable bolt and nut assemblies 25'. Bolt and nut assemblies 26 connect the angles 24 to a drawing board 27, and the other angle 24' is connected to the opposite side of the drawing board 27 by bolt and nut assemblies 26, Figure 2.

For preventing the board 27 from pivotally moving too far in a counter-clockwise direction, 50 a washer 28 is secured to the lower end of the quadrant 20 by a set screw 29. A similar washer 28' is secured to the lower end of the other quadrant 20' by a set screw 29'. The washers 28 and 28' are adapted to contact the clamp brackets 21 and 21' in the event that the board

27 is pivoted too far, to thereby limit counter-clockwise pivotal movement of the board 27. Extending along an edge of the drawing board 27 and secured thereto, is a strip 30 which is adapted to prevent cards and the like from sliding off the board while the cards are being painted. The strip 30 is also adapted to be used as a guide for laying off lines on cards.

A manually operable means is provided for moving the drawing board 27 towards and away from the user so as to enable the user to work efficiently and comfortably. This means includes a pair of bearings 31 and 32, Figure 2, the bearings 31 and 32 extending between the angles 18 and 18' and secured thereto. A shaft 33 is rotatably supported by the bearings 31 and 32, and a hand wheel 34 is secured to one end of the shaft 33 for moving the latter. Secured to the other end of the shaft 33 is a grooved or recessed drum 35 which has a rope or cable 36 trained thereover.

One end of the rope or cable 36 is secured to a buttonhead 37 which is anchored in an angle bracket 38, the angle bracket 38 being secured to the undersurface of the board 27 adjacent its lower edge, by means of bolts 39. The other end of the rope or cable 36 is connected to a threaded stud 40 which is arranged in engagement with an angle bracket 41, the angle bracket 41 being secured to the undersurface of the board 27 by bolts 42. A nut 43 is arranged in engagement with the stud 40 and by proper rotation of the nut 43, the tension on the rope or cable 36 can be adjusted as desired.

Arranged off center with respect to the bearing 32 and projecting therefrom is a pin 44 which is adapted to seat in one of a plurality of spaced openings 45 that are arranged in the end of the drum 35. Thus, when the pin 44 is in one of the openings 45, rotation of the drum 35 will be prevented so that the drawing board 27 will remain immobile in its adjusted position. A coil spring 46 is circumposed on the shaft 33 and the coil spring 46 is interposed between the bearing 32 and a collar 47 which is secured to the shaft 33. This coil spring 46 normally maintains or urges one of the openings 45 into engagement with the pin 44 to thereby lock the drum 35.

Thus, it will be seen that the above described apparatus enables the drawing board 27 to be shifted to and from the user. To shift the drawing board 27, a slight inward pressure is exerted on the hand wheel 34 to thereby disengage the opening 45 in the drum 35 from the pin 44, thereby enabling rotation of the hand wheel 34. The hand wheel 34 can be rotated in either direction so that the board 27 can be moved towards and away from the user, since the ends of the rope or cable 36 are connected to the opposite ends of the drawing board 27. As soon as the pressure on the hand wheel 34 is released, as when the drawing board 27 has been set in the desired position, the coil spring 46 will return the shaft 33 and drum 35 to the position

shown in Figure 5 wherein the drawing board will be locked in the desired position. Further, the construction of the table is such that the table can be readily disassembled and folded into a compact unit for shipment purposes.

From the foregoing, it is apparent that a table has been provided which is especially suitable for sign and show card writers. The table, however, can also be used for general drawing as desired. The drawing board 27 can be readily adjusted and locked in any position from horizontal to vertical as previously described. Further, the drawing board 27 can be moved towards and away from the user by the previously described structure, so that the user can work comfortably and efficiently. All of the adjustments can be quickly and easily made by the operator without requiring assistance from anyone else.

20 What I claim:

A writer's table having a supporting body including a pair of spaced parallel vertically disposed frame members, horizontally disposed channels extending between said frame members and secured thereto, a pair of channel-shaped tracks pivotally connected to said frame members, a runner slidably arranged in each of said tracks, a drawing board connected to said runners, a clamp bracket secured to the upper end of each of said frame members, a quadrant connected to each of said tracks and slidably projected through said clamp brackets, a thumb screw for maintaining said quadrants removable in their adjusted position, the improvement comprising means for causing adjustable sliding movements of said drawing board and said means including a pair of angle irons extending between said tracks and secured thereto, a shaft arranged between said angle irons and rotatably supported thereby, a hand wheel secured to one end of said shaft for manually moving the latter, a grooved drum connected to the other end of said shaft, a cable trained over said drum and having its ends connected to opposite ends of said board, there being a plurality of spaced openings in one end of said drum, a bearing arranged adjacent said drum and connected to said angle member, a pin projecting from said bearing and normally secured to one of the openings of said drum preventing accidental movement of said drawing board.

PERCY W. THOMPSON.
